Primary Examiner — Christian P. McLean(74) *Attorney, Agent, or Firm* — Brooks Kushman P.C.; Michael Spenner(57) **CLAIM**

The ornamental design for a vehicle rear bumper cover, as shown and described.

DESCRIPTION

FIG. 1 is a top left perspective view of a left vehicle rear bumper cover. The novel design also includes an embodiment of a right vehicle rear bumper cover which is mirror symmetrical to the embodiment of FIGS. 1-9, and is therefore not separately illustrated.

FIG. 2 is a bottom front perspective view thereof;

FIG. 3 is a top rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

1 Claim, 9 Drawing Sheets(56)
